DRINKING GLASS OR SIMILAR ARTICLE

Hyman J. Warsager, Cedar Grove, N. J.

Application September 17, 1956, Serial No. 42,961

Term of patent 14 years

(Cl. D36—8)

Fig. 1 is a perspective view of a drinking glass showing my new design;

Fig. 2 is a perspective view thereof rotated substantially 120 degrees clockwise; and,

Fig. 3 is a perspective view thereof rotated substantially 240 degrees clockwise.

The drawing is stippled to indicate contrasting colors or hues.

I claim:

The ornamental design for a drinking glass or similar article, as shown and described.
